ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE VALVE ENGINE

Original application filed September 28, 1927, Serial No. 222,499. Divided and this application filed March 11, 1929. Serial No. 345,983.

This invention is a division of my co-pending application Serial No. 222,499, filed September 28, 1927, and relates to internal combustion engines and refers more particularly to the sleeve valve type of engine ordinarily known as the "Burt-McCollum" engine, in which a single sleeve valve is given a combined reciprocating and oscillating movement in controlling the engine intake and exhaust. In this type of engine it is customary to locate the sleeve valve between the working piston and the cylinder, the end of the sleeve remote from the engine crankshaft ordinarily moving in a sleeve pocket formed by a cylinder head projecting inwardly of the cylinder and spaced therewithin. The reciprocating movement of the sleeve within the sleeve pocket heretofore caused the gases entrapped therein to be compressed and expanded resulting in undue irregularities in the movement of the sleeve valve operating mechanism; inducing leakage of gases relatively between the combustion chamber and cylinder ports; and tending to pump lubricating oil into the sleeve pocket.

One of the objects of my invention resides in the provision of simple and efficient means for balancing the pressures of the sleeve pockets in a multi-cylinder engine by interconnecting the sleeve pockets with a common pressure equalizing manifold. This equalizing manifold may be connected to suction means such as the engine oil pump or intake manifold assisting in the equalization of the pressure in the sleeve pockets and also serving to withdraw therefrom any accumulation of lubricating oil or other deposits which might otherwise become entrapped and burned leaving objectionable residues including a deposit of carbon.

With these and other objects in view the invention consists in the novel combination and arrangement of parts more particularly hereinafter described and claimed.

With reference to the accompanying drawing in which like reference characters illustrate corresponding parts,

Fig. 1 is a perspective elevation view of the engine, a section being taken transversely through a typical cylinder and illustrating

somewhat diagrammatically one embodiment of my sleeve pocket pressure equalizing device and sleeve pocket deposit removal device, and

Fig. 2 is a fragmentary view of a modified form of manifolding for the pressure equalizing and deposit removing.

In the drawing reference character A represents the engine comprising one or more cylinders 10 closed at one end by a cylinder head 11 projecting within the cylinder and spaced therefrom to form a sleeve valve pocket 12. Between piston 13 and cylinder 10 is located one or more of the well known types of sleeve valves, the illustration comprising a single sleeve valve 14 provided with intake and exhaust ports 15 and 16 respectively cooperating with cylinder intake and exhaust ports 17 and 18 in controlling the cyclic events of the engine. The sleeve valve 14 may be given a combined reciprocating and oscillating movement with respect to the cylinder and sleeve axes in a well known manner whereby a point on the sleeve valve moves in a closed path curve relatively to the cylinder wall. The end of the sleeve valve moves axially within the sleeve pocket, the sleeve ports registering with the cylinder ports and then moving into the sleeve pocket. Such parts thus far described are well known in the art.

In order to overcome the aforesaid disadvantages due to the movement of the sleeve valve in the pocket 12 I have provided a sleeve valve pocket equalizing manifold 19 having branches 20 registering with the cylinder passages or ports 21 which respectively communicate with the sleeve pockets 12 of the various cylinders 10, preferably at or near the outer ends of the sleeve pockets so that the sleeve valves 14 will not cover the passages 21 at the outer extreme position of their movement. By reason of the inter-connection of the sleeve pockets through the manifold 19 the pressures in the various pockets 12 will, at all times be equalized. Due to the timing of the engine the various sleeve valves will be in different relative positions at a given time so that when one sleeve 14 is moving outwardly in the pocket 12, for example,

another sleeve moving inwardly at this time will be subjected to the same pressure from its sleeve pocket 12. The equalization of pressures in the sleeve pockets produces a 5 better gas seal and a more even valve operating movement as aforesaid.

If desired, the manifold 19 may be connected through pipe 22 with a suction device such as the usual engine oil pump 23. The 10 pump outlet 24 may lead to the usual engine bearings with an intake 25 connected to the crank case oil supply 26. Thus the equalization of the sleeve pockets is facilitated by the pump 23 and lubricating oil and other 15 deposits will be withdrawn from the sleeve pockets into the manifold 19 whence they will be conducted to the crankcase by the suction pipe 22.

Referring to Fig. 2, instead of connecting 20 the equalizing manifold with the suction of an oil pump as in Fig. 1, I have provided a suction trap 27, suction being produced in the trap preferably by a connection 28 with the intake manifold 29. The trap 27 is connected by suction pipe 22^a with equalizing manifold 19. The trap 27 serves to catch the oil and other deposits removed from the sleeve pockets 12, such accumulated oil and residue indicated at a level 30 being drained 30 into the crankcase if desired by a return pipe 31. A valve 32 is normally seated by a spring 33 which, however, will be compressed under a predetermined weight of accumulated oil in the trap, thus permitting 35 the residue to periodically drain into the crankcase. If desired a valve 34 may be provided in the passage 28, a valve spring 35 permitting unseating of the valve whenever the suction in the intake manifold reaches a 40 predetermined amount.

If the equalization of the sleeve pockets is desired to be dispensed with, the suction passages 21 may be independently connected with the suction producing means, thus utilizing 45 the device solely for sleeve pocket deposit removal as will readily be understood.

What I claim as my invention is:

1. A sleeve valve internal combustion engine comprising in combination, a plurality 50 of cylinders each having reciprocable sleeve valve means and a sleeve valve pocket receiving one end of the sleeve valve means, a sleeve valve pocket pressure equalizing manifold, means establishing communication between the manifold and sleeve valve pockets, an oil pump, and a conduit connecting said pressure equalizing manifold with the intake of said pump.

2. A sleeve valve internal combustion engine comprising in combination, a plurality 60 of cylinders each having reciprocable sleeve valve means and a sleeve valve pocket receiving one end of the sleeve valve means, a sleeve valve pocket pressure equalizing manifold, means establishing communication between 65

the manifold and sleeve valve pockets, an oil pump, a conduit connecting said pressure equalizing manifold with the intake of said pump, a supply of lubricating oil, means establishing communication between the oil supply and the intake of said pump, and a conduit for conducting oil from the pressure side of the pump to the engine bearings. 70

3. A sleeve valve engine comprising in combination, a cylinder, sleeve valve means, 75 a piston, a sleeve pocket structure, an oil pump, and a conduit connecting the sleeve pocket with the oil pump suction for extracting deposits from said sleeve pocket.

4. A sleeve valve engine comprising a plurality of cylinders each provided with sleeve valve means and a pocket structure receiving the sleeve valve means, an equalizer manifold communicating with the sleeve pockets of said cylinders, an oil pump, and a conduit connecting said equalizer manifold with the oil pump suction. 80

In witness whereof, I hereunto subscribe my name this 8th day of March, A. D. 1929.
